COIN-CONTROLLED ACTUATING
MECHANISM

Clark H. Weaver, Berkeley, Calif.

Application April 3, 1948, Serial No. 18,816

4 Claims. (Cl. 194—92)

1

The present invention relates to coin-controlled actuating mechanisms of the type employed to operate the release mechanism of vending machines to individually dispense the articles stored in the magazines thereof. Such actuating mechanisms are generally arranged to be normally in a disabled condition and may be rendered effective for single operation by the introduction of the proper coin or coins for which the mechanism is designed.

The necessity of designing such actuating mechanisms for operation with a particular type of coin or coins corresponding to the price of the vended article, limits the use of the vending machine to articles of identical price. In practice, however, it is frequently desirable to employ a vending machine for selling articles of different prices. Thus, it is highly desirable to have one and the same machine vend both, the Sunday as well as the week days editions of newspapers, to avoid the necessity of using different machines on week days and on Sundays.

Broadly it is an object of the present invention to furnish a manually operable coin-controlled actuating mechanism for vending machines and the like which is simple in construction and effective in operation.

More specifically it is an object of the present invention to provide a coin-controlled actuating mechanism for vending machines which may selectively be adjusted for operation with any one of a plurality of different coins.

It is yet another object of the present invention to furnish a coin-controlled actuating mechanism of the type referred to, that may selectively be adjusted to positions requiring either a selected one or all of a plurality of different coins to be rendered operative.

Additionally it is an object of the present invention to furnish an actuating mechanism, of the type referred to, which may selectively be adjusted to positions wherein (1) only a selected one of two coins or (2) either of said coins or (3) only a combination of both is capable of rendering said mechanism operative.

Furthermore it is an object of the present invention to provide an arrangement adapted to convert uni-directional actuating strokes, such as are provided by coin-controlled actuating mechanisms of the type referred to, into reciprocative actuating strokes to permit employment of the mechanism of my invention in vending machines of the kind requiring reciprocative actuation.

These and other objects of my invention will

2

be apparent from the following description of the accompanying drawings which illustrate a preferred embodiment thereof, and wherein:

Figure 1 is a rear elevation of a coin-controlled actuating mechanism embodying my invention.

Figure 2 is a fragmentary side elevation of the same mechanism viewed in the direction of the arrows 2—2 in Figure 1.

Figure 3 is an opposite side elevation of the actual coin-controlled unit viewed in the direction of the arrows 3—3 in Figure 1.

Figure 4 is an enlarged detail view of part of the latching mechanism employed in the coin-control unit.

Figure 5 is a side elevation of the coin-control unit shown in a manner similar to Figure 2 but in a different operational position.

Figure 6 is another side elevation of the coin-control unit, shown in a manner similar to Figure 2, but in yet another operational position and with its outer wall and part of the associated lever mechanism omitted to expose the structure underneath.

Figure 7 is a horizontal section of the coin-control unit viewed in the direction of the arrows 7—7 in Figures 1 and 2.

Figure 8 is a vertical cross-section through the coin-control unit taken along the line 8—8 in Figure 2.

Figures 9 and 10 are fragmentary side elevations, similar to Figure 6, of a modified embodiment of the coin-control unit in different operational positions, and

Figure 11 is a fragmentary rear elevation of the actuating mechanism proper, shown in a manner similar to Figure 1, but in a different operational position.

Having reference to Figures 1 and 2, the actuating member of the mechanism of my invention is formed by a plate 10 arranged for vertical sliding movement along the inner surface of a stationary wall 11 that may form part of, or may be rigidly secured to, the front or side wall of a newspaper vending machine. To properly guide the plate 10 in its actuating movement, suitable filets 12 may be arranged along the outer vertical edges of the wall 11 in spaced relation thereto to form guide grooves 13 as best shown in Figure 7. The sliding plate 10 carries an outwardly directed stud 15 (Figures 2 and 7) which protrudes through an elongated vertical slot 16 provided in the wall 11 (Figure 1), with a suitable operating knob (not shown) mounted upon the outwardly projecting end thereof. A contraction

55 spring 18 tensioned between the upper end of the

slide 10 and a point 19 of the stationary wall 11 yieldably maintains said slide in the upward position illustrated in Figures 1 and 2, where in its stud 15 abuts the upper end of the elongated vertical slot 16.

Means are provided which ordinarily prevent depression of the actuating slide 10 from said upward position, and for this purpose said slide carries a pair of brackets 20 and 21 which support a horizontal shaft 22 upon which are rotatably mounted two parallel bell crank levers 23 and 24. Both of said bell crank levers possess upwardly directed elongated arms 25 and 26 respectively the upper ends of which are provided with inwardly directed studs 27 and 28 respectively as best shown in Figure 8. These studs protrude into and slidably engage two vertical slots 29 and 30 respectively formed in opposite faces 31 and 32 of a latching unit 33 disposed intermediately of said lever arms 25 and 26 and rigidly supported from the stationary wall 11 (Figures 1, 2, 3, 7 and 8).

At their upper ends both of the slots 29 and 30 are expanded to form recesses 34 or 35 respectively which are shaped somewhat in the manner of a uni-lateral barb having an inwardly declined bottom edge *a* and a lateral edge *b* ascending obliquely to the crest of its respective slot, as best shown in Figure 4. Both of said recesses 34 and 35 extend in the same direction which is to the left as viewed in Figure 2 and to the right as viewed in Figure 3. Contraction springs 36 tensioned between suitable points of the bracket structure 20, 21 and the tails 38 of the bell cranks 23 and 24 constantly urge the studs 27 and 28 in the direction of the recesses 34 and 35 respectively, but when the slide 10 is in its uppermost position the oblique edges *b* of said notches maintain said studs in vertical alignment with the slots 29 and 30 respectively as shown in Figures 2 and 3. As soon as the slide 10 is depressed, however, the springs 36 urge the studs 27 and 28 into the recesses 34 and 35 wherein they hook over the edges *a* and thus positively prevent further downward movement of said slides as illustrated in Figure 5.

The unit 33 comprises means effective, upon payment of the proper coinage, to prevent engagement of the studs 27, 28 with the horizontal edges *a* of the recesses 34 and 35 and thus permit a full actuating stroke of the slide 10. For this purpose the slots 29 and 30 are associated with coin channels 40 and 41 respectively (Figures 2, 3 and 7) which are adapted to conduct coins inserted therein into positions in which they cover the recesses 34 and 35 and thus block entrance of the studs 27 and 28. Since both the channels 40 and 41 are of practically identical construction, except for their physical dimensions which differ according to the dimensions of the coins for which they are designed, only the coin channel 40 will be described in detail hereinafter, it being understood that the same description applies logically to the twin channel 41.

Having specific reference to Figure 2 the channel 40 commences with a coin slot 42 which is preferably situated at a point exteriorly of the machine wall 11 some distance above the previously described operating stud 15 of the actuating slide 10. The initial portion of the channel 40 is only slightly inclined and extends to a point above and somewhat beyond the slot 29 where it changes abruptly into an almost vertically descending passage 43. At about the level of the

recess 34 this passage 43 forms a short but pronounced kink 44 which extends toward and beyond the slot 29 in such a manner that its concave portion passes directly behind, and communicates freely with, the upper portion of said slot including its recess 34, as shown in Figures 2, 5 and 6.

The concave portion of the passage 43 communicates also with a laterally adjacent chamber 45 provided in the interior of the unit 33 which accommodates a spring pawl 46 that is pivoted to the walls of said unit at a point 47 above the recess 34. This pawl is composed of a substantially horizontal tail 48 and a substantially vertical arm 49 which has a concave recess 50 in its clockwise edge and terminates into an elongated blade-like extension 51 as shown in Figures 2, 5 and 6. A spring 52 disposed between said tail 48 and a stationary point of the unit 33 urges said pawl into a clockwise position in which its blade 51 bears against the partition 53 between the lower portions of the coin passage 43 and the slot 29 while its recess 50 forms the concave wall of kink 44 in said passage 43 as shown in Figures 2 and 5.

The lower corner of the concave recess 50 is somewhat accentuated to form a shoulder 54 which restricts the coin passage 43, when the pawl 46 is in its above described clockwise position, and as a result thereof a coin of proper size dropped into the channel 40 will be retained between the shoulder 54 and the hump 55 in the opposite wall of the passage 43 and will assume the position illustrated in phantom lines in Figure 6 in which it covers the recess 34. This renders it impossible for the stud 27 to enter into, and engage the edge *a* of, the recess 34 and as a result thereof said stud is guided into the open vertical portion of the slot 29 when the slide 10 is depressed, permitting a full downward stroke of said slide (provided the mechanism associated with the twin channel 41 is in the same condition). As the stud 27 enters into, and descends, the vertical portion of the slot 29, it strikes against the upper edge of the shoulder 54 and cams the pawl 46 in counterclockwise direction as shown in full lines in Figure 6. Thus, the obstructing point of the shoulder 54 is withdrawn from the passage 43 permitting the coin 50 to slide to the bottom of the coin channel 40 from where it may drop into a detachable coin collector magazine 57 indicated in dotted lines in Figure 2.

As soon as the customer releases the operating handle of the slide 10, the restore spring 18 returns said slide to its original level and thus repositions the lug 27 in the crest of the slot 29, permitting the spring 52 to restore the pawl 46 to its clockwise position in which its shoulder 54 extends across the slot 29 and restricts the width of the coin passage 43 as shown in Figures 2 and 5. Thus, the actuating mechanism of the invention is again in its normal condition in which it is locked against operation until a new coin has been inserted into the channel 40. It is important that the length of the blade 51 of pawl 46 be properly proportioned with respect to the depth to which the slide 10 may be depressed as determined by the depth of the elongated slot 16 in the machine wall 11; that is to say: said blade must be sufficiently long to remain in contact with the stud 27 when the latter is fully depressed, otherwise the pawl 46 might resume its clockwise position above the stud 27 before said stud has returned to its up-

ward position, and thus prevent return of said stud to the crest of the slot 29 resulting in complete disruption of the described control mechanism.

As previously pointed out the coin channel 41 and its control pawl 58 (Figure 3) are identical in construction with the above described coin channel 40 and its pawl 46, except for their physical dimensions which may differ according to the size of the coins for which they are designed. For instance, in the particular embodiment illustrated in the accompanying drawings the channel 40 may be designed for a 5-cent coin while the channel 41 may be adapted for operation with a 10-cent coin. In such a case a prospective buyer must insert a nickel into the channel 40 and a dime into the adjacently situated channel 41 before the slide 10 can be fully depressed to release one of the articles contained in the magazine of the associated vending machine. The present invention, however, provides means to selectively adjust the described arrangement to conditions where only one or the other of said coins is required to render the actuating mechanism operative. For this purpose a lever 60 is pivoted to the wall 31 of the locking unit 33 with one of its ends arranged to project laterally beyond said unit to form a conveniently accessible setting handle 61 (Figures 2 and 7) while its other end 62 is adapted to cover the recess 34. Hence by turning the lever 60 from the position shown in full lines in Figure 2 to a position in which it covers the recess 34, the latching arrangement 27/34 may be disabled in the same manner as if a nickel were lodged between the shoulder 54 of the pawl 46 and the hump 55 in the opposite wall of the passage 43, and as a result thereof payment of only a dime into the channel 41 is sufficient to release the actuating slide 10 for effective operation. A similar lever 64 (Figures 3 and 7) may be arranged at the opposite face 32 of the unit 33 permitting the other latching arrangement 28/35 to be disabled at will, to establish conditions wherein only a nickel is required to release the actuating mechanism for effective operation.

Under certain conditions it may be desirable to adjust the locking unit 33 in such a manner that either a nickel or a dime will be effective to release the actuating slide 10 for operation. For instance, the price of a newspaper may actually be a nickel, but customers who find themselves without the proper change may rather spend a dime than go without a paper. To enable the arrangement of my invention to take care of situations of this kind, the bell cranks 23, 24 may possess downwardly extending arms 65 (Figures 2, 3 and 8) which are provided with horizontally aligned apertures 66 adapted to removably receive a bar or rod 67. When the bar 67 is pushed through said apertures, as indicated in phantom lines in Figure 8, the bell cranks 23, 24 form an integral structure and turn in unison upon their common shaft 22. Hence, the presence of a coin in the kink 44 of either the coin channel 40 or the coin channel 41 will be sufficient to restrain both of the studs 27, 28 from entering their respective latching recesses 34 or 35 so that payment of either a nickel or a dime will be effective to release the actuating slide 10 for operation.

In certain instances the price of a vended article may be such that it can only be made up by a plurality of identical coins. The coin-control unit of the present invention can easily be modi-

fied to take care of such situations as demonstrated by Figures 9 and 10 which illustrate a coin control unit 33' that is adapted to release the actuating mechanism upon payment of three 1¢ coins. In this modified coin-control unit the descending branch 43' of the coin channel 40' drops vertically to a point a predetermined distance below the level of the latching recess 34' where it forms an inwardly directed hump 55' of limited altitude. The control pawl 46' is similar in shape and construction to the pawl 46 of the embodiment illustrated in Figures 2, 5 and 6, except that its blade 51' is materially extended in downward direction to a point below the level of the hump 55', and thus forms the main part of the front wall of the passage 43' in place of the partition 53' which has been reduced in size to an extent where it is scarcely more than a stop determining the extreme clockwise position of the blade 51'. Furthermore, the shoulder 54' of the pawl 46', though still extending across (or at least into) the slot 29', is less pronounced so that it no longer restricts the passage 43' and is of a smoothly rounded contour so that a coin dropped into the channel 40' is dependably guided into the lower portion of said passage 43' where it will lodge between the hump 55' and the yieldable blade 51' of the spring pawl 46' as shown in Figure 9. The exact position of the hump 55' is such that three superposed 1¢ coins are required for the uppermost coin to cover the latching recess 34', as likewise shown in Figure 9. Therefore, when a prospective buyer operates the actuating mechanism after he has placed three coins into the coin channel 40', the uppermost coin cams the latching stud 27' past the recess 34' into the vertical portion of the slot 29' and against the upper edge of the shoulder 54'. As a result thereof the descending stud 27' forces the spring pawl 46' in counterclockwise direction so that the blade 51' to the right of the coins is withdrawn and said coins are permitted to slide or roll over the hump 55', as shown in Figure 10, and drop into a coin collector box that may be provided at the bottom end of the passage 43' (not shown).

While the hump 55' in the embodiment illustrated in Figures 9 and 10 is positioned such a distance below the latching recess 34' that three superposed coins are required for the uppermost coin to disable the latching arrangement 27'/34', it will be understood that the device illustrated in said figures may readily be designed for operation with two or four or any other number of coins by appropriately positioning the hump 55' closer to or further away from the level of the latching recess 34'. Furthermore, to permit convenient adaptation of a coin-control unit, of the type described, for operation with a different number of coins, the rear wall of the unit 33' may be made exchangeable so that said unit may selectively be fitted with any one of a variety of different rear walls in which the humps 55' are positioned at different altitudes depending upon the number of coins intended to render the actuating mechanism effective.

While the actuating mechanism so far described provides positive actuation in one direction only, corresponding to downward movement of the slide 10, certain vending machines, such as the one disclosed in my copending application Serial No. 731,526 filed on February 28, 1947, now Patent 2,546,352, issued March 27, 1951, require reciprocative actuation to successively release the articles stored in their magazines. The present invention, therefore, may comprise means

for converting the uni-directional actuation supplied by successive downward strokes of the slide 10 into alternately oppositely directed actuating strokes. For this purpose a lever 71 is pivoted to the slide 10 at 72 and is yieldably maintained in a vertical position by a contraction spring 73, tensioned between its upper end and a suitable stud 75 secured to the slide 10 at a point vertically above said upper end as shown in Figure 1. The lower end 76 of the lever 71 projects beyond the lower edge of the slide 10, and pivoted to the stationary wall 11 at a point 77 vertically below said pivot 72 is a lever 78 having somewhat the shape of a downwardly pointing deltoid the shallow end of which is formed by two symmetrically shaped concave edges 79 and 80 descending laterally from a centrally positioned common point or peak 81. A contraction spring 82 disposed between the downwardly directed crest 83 of the deltoid 78 and a stationary point 84 intermediately of, and in vertical alignment with, the pivots 72 and 77 urges the deltoid 78 into contact with one or the other of a pair of stops 86 and 87 disposed at either flank of said deltoid predetermined equal distances apart from a center line $x-x$ determined by the pivot points of the levers 71 and 78. Thus, the deltoid 78 presents one or the other of its concave edges 79, 80 to the end 76 of the lever 71 as shown in Figure 1, wherein the right flank 88 of said deltoid is held against the right hand stop 86 with its crest 83 situated to the right of the center line $x-x$. In this position the deltoid 78 presents the right one of its concave edges to the end 76 of the lever 71, and whenever the slide 10 is pressed, the descending point 76 of the lever 71 strikes against the steeply sloping inner portion of said concave edge and is immediately deflected toward the outer end thereof, until it strikes fully against the pit of said concave edge to the right of the center line $x-x$ (Figure 11) and thus imparts a rotary momentum to the deltoid 78 swinging it in clockwise direction against the urgency of the contraction spring 82. As the slide 10 continues its descent, the crest 83 of the deltoid 78 is eventually pushed beyond its point of maximum distance from point 84, as represented by the center line $x-x$, permitting spring 82 to contract and force the deltoid 78 further in clockwise direction until its left hand flank 89 strikes against the left stop 87. The deltoid 78 is now in a position which is the symmetrical counterpart of its original position, with its crest 83 situated an identical distance to the left of the center line $x-x$ as shown in phantom lines in Figure 11. In this position the deltoid 78 presents the left one of its concave edges to the point 76 of the lever 71 that has meanwhile returned to its original position under the influence of the restore springs 18 and 73. Renewed depression of the actuating slide 10 will repeat the described performance in a symmetrically opposite direction and will re-position the crest of the deltoid 78 to the right of the center line $x-x$. Thus, successive depressions of the slide reciprocate the crest 83 of the deltoid 78 between the extreme left and right hand positions illustrated in Figures 1 and 11, and will thus enable a horizontal bar 90 pivoted to the crest of the deltoid 78 to provide positive reciprocal actuation.

While I have explained my invention with the aid of a preferred embodiment thereof, I do not wish to be limited to the constructional details shown and described, because other embodiments

based on the same principles and combining the same dependability of performance with simplicity of construction may readily be devised by those skilled in the art without departing from the scope or spirit of my invention. Thus, if it should be desirable to have a greater choice of adjustments to different coins or combinations thereof, it is only necessary to extend the coin control arrangement by installing additional coin channels and associated control mechanisms at one or both sides of the unit 33 and provide a corresponding number of properly correlated bell cranks upon the shaft 22.

Having thus described my invention and the manner in which it is to be performed, what I claim is:

1. A coin-controlled actuating mechanism comprising an actuating member constrained to move in vertical direction, and yieldably held in an upward position, an arm pivotally supported from said actuating member, said arm having a latching projection, a vertical guide surface, spring means disposed to urge said projection against said guide surface, said surface having a recess forming a latching edge and an obliquely ascending camming edge, a descending coin channel in communication with said recess and a yieldable pawl arranged to protrude into the path of said projection at a point below said recess and restrict said channel to retain coins dropped thereto in a position wherein the cover said recess preventing engagement thereof by said projection and direct said projection against said yieldable pawl.

2. Arrangement according to claim 1 wherein said recess is located at the upper end of said guide surface.

3. A coin-controlled actuating mechanism comprising a descending coin channel having a pair of end walls and a pair of side walls, an aperture provided in one of said side walls; an actuating member arranged to move along a pre-established path and having a latching element adapted to engage said aperture at a predetermined point of said path to obstruct further movement of said actuating member; and retaining means disposed in said channel a distance below said aperture to enable the uppermost one of a predetermined number of coins to cover said aperture and prevent engagement thereof by said latching element, said retaining means comprising an inwardly directed hump provided on one of said end walls and a yieldable pawl disposed to form the opposite end wall of said channel at the level of said hump; said actuating member being arranged to force said yieldable pawl away from said channel upon movement beyond said predetermined point.

4. Arrangement according to claim 3 wherein the end wall possessing said retaining hump is an exchangeable component.
